BOARD GAME AND APPARATUS THEREFOR

Harvey J. Griffith, Denver, Colo.

Application April 11, 1938, Serial No. 201,221

3 Claims. (Cl. 273—136)

This invention relates to improvements in board game and game apparatus and is intended to provide a game for trading in various commodities in a manner dependent entirely on skill and intelligence as distinguished from chance.

It is well known that the values of stocks, real estate commodities, business receipts, etc., vary in accordance with certain trends and statistical conditions. The trader that prospers most is the one who recognizes the significance of the different trends and how they affect values. Thus, an increasing trend in unemployment produces a decrease in earnings and purchasing power which affects almost every article of commerce adversely.

A threat of war may produce an increase in the price of certain war materials such as copper, steel, etc. Low oil reserves have a tendency to produce an increase in the price of oil and large reserves have the opposite effect.

It is an object of this invention to produce a game, the successful playing of which depends on the skill with which the players can judge the effect of national and international news on the holdings that they have and on the general list as a whole and the one that can arrange his trade so as to profit the most from the information available will win.

In order to more clearly describe the invention so that it can be readily understood reference will now be had to the accompanying drawings in which the several pieces of apparatus employed have been illustrated and in which:

Figure 1 is a face view of a board employed to give the prices for all listings for each month of the year;

Figure 2 is a transverse section taken on line 2—2 Fig. 1;

Figure 3 is a longitudinal section taken on line 3—3 Fig. 1;

Figure 4 is a view of the slide portion of the board apparatus shown in Fig. 1 and shows the several listings that players may deal in, also the prices for the month of December;

Figure 5 is a view showing the three groups of numbers representing the prices, which are partially concealed by the slide shown in Fig. 4;

Figure 6 is a view showing the rear view of a player's card, and shows a computing table for determining quickly and accurately the cost of any block of stock or other article listed on the board.

Figure 7 shows the reverse side of the card, shown in Fig. 5, on which is contained a printed

list which is a duplicate of the listings shown on the slide in Fig. 4;

Figure 8 is a top plan view of the "business box" showing the different compartments;

Figure 9 is a transverse section taken on line 9—9 Fig. 8;

Figure 10 is a section taken on line 10—10 Fig. 8;

Figure 11 shows a portion of a roller slide; and

Figure 12 shows samples of the script money and sales tickets employed.

In playing this game one person, who may or may not be a player, acts as manager and has in his possession the business box shown in Figs. 8—11. This box is provided with several compartments for keeping the money and the sales slips. In the embodiment illustrated there are nine compartments 15 of the proper size to receive the script paper money illustrated in Fig. 12 and indicated by reference numeral 16. The box has seven smaller compartments, designated by numeral 17, which serve as safety deposit boxes and in which are filed the customers' sales slips, designated by numeral 18 in Fig. 12.

The lowermost of the series of compartments 17, and which is designated 17a is for the reception of coins, or slugs representing coins.

There is another series of small compartments 19, five being shown, one for each article of commerce dealt in, namely, stocks, produce, metal, live stock and business opportunities. In the upper end of the business box is a large compartment 20 in which are mounted for rotation two spaced rollers 21 to which the ends of a tape 22 are fastened. Each roller has a knob 23. Compartment 20 has a rectangular opening 24 through which the printed surface of strip 22 can be seen. The upper edge of opening 24 has a plurality of equally spaced arrow points 25, the one farthest to the left being marked "55" and the one farthest to the right being marked "110." There are twelve arrow points, each designated by a number that differs from the adjacent number by five. The numbers just referred to are marked "Commodity price level." Strip 22 is divided into twelve major sections, one for each month of the year. At the very beginning there is a section, marked 26, which merely gives instructions for playing.

Following section 26 is section 27, headed "January trends (listen closely)." Under this heading, and following dates, are news items tending to show the trends of business. Following section 27 is a section 28 headed "Tips 55

(profit by them)." Under this heading are certain questions and statements of fact. The correct answers to the questions gives the initial of the name of a group of products or stocks and the statement tells how the prices of the corresponding products whose names begin with the same letters will respond in the near future. Following section 28 is a short paragraph 29 giving instructions for closing the business for the month and for preparing for next month's business.

Each month, except December, has three sections, similar to the one for January, but for December there is a single section only, which 15 explains how the business of the previous eleven months is to be closed.

In order to show with greater particularity the nature of the information contained on strip 22, a short section is here reproduced.

20

To start the game

Each player now selects \$500 worth of some commodity, such, produce, metals, or some business within the \$500 range. These are the only assets with which a player is expected to prosper. Watch all trends and tips, as a good investment in the earlier stages of the game will greatly increase assets for later investments.

The manager will now read the January trends 30 and tips. Follow instructions from month to months.

January trends (listen closely)

Jan. 1. The bureau of mines at Washington at this date reports a decrease of two million barrels of crude oil.
 35 Jan. 3. A bearish tone is noted in the cotton market to-day.
 Jan. 6. Wall street hears that motor companies are planning large expansion programs.
 40 Jan. 9. Construction work shows increased activity in all sections of the United States.
 Jan. 12. Sugar trading to-day shows little activity.
 45 Jan. 15. Housewives meat strike is declared throughout many sections of the U. S.
 Jan. 19. Federal elevators show a surplus of corn.
 Jan. 24. U. S. reduces the duties on imported raw silk.
 50 Jan. 27. Potato crop control wins throughout the western growers association.
 Jan. 30. One million bushels of corn was tendered in Chicago for monthend settlements of contracts.

55

Tips (profit by them)

1. Finland has what form of government?
 Stocks are up 50 to 75 percent.
2. Are the flukes of a whale's tail vertical or horizontal?
 Live stock show increase.
3. Who said "Go west, young man, go west?"
 Stocks up.
4. What is the capital of Russia?
 Metals up.
5. What period of time is granted a boxer to regain his feet after being knocked down?
 Metals show a 35 to 50 percent gain.
6. How many members has the supreme court of the U. S.?
 Stocks up 50 to 75 percent.
7. How many keys are there in an octave on a piano?
 Stocks up.

8. With what science does the nebular hypothesis deal?
 Stocks up.
9. Who said, "you can fool some of the people all of the time, and all of the people some of the time, but you cannot fool all of the people all of the time?"
 Metals down.
10. What was the name of Tom Mix's famous horse?
 Live stocks down.
 Pay each player \$200 salary for January.
 Pay business profits to players owning business.
 Business transaction period. (Players now 15 buy or sell according to their judgment.)
 Shift sheet slot to February prices.

February trends (be careful)

20

Tips

Instructions

March trends (watch for opportunities)

25

Tips

Instructions

Etc. to December

30

December

December is cash-in month.

Pay each player \$200 salary for December.
 Pay business profits to players owning business.
 Each player now cashes in all his possessions to the manager of the game at the December prices.

The player whose assets and cash totals the most wins the game, therefore prospers the most.

It will be noted from Fig. 11 that a line 30 extends the entire length of strip 22. This line designates the commodity price level, the value of which is determined by comparing its position with the arrow points 25.

The trends contained in section 27 and corresponding sections for each month govern the general outlook for speculation, as well as business in general. Prices fluctuate from month to month according to the trends, whose purpose is to reflect rise and fall during the progress of the game, as well as to show high and low business cycles. Resumes of the economic news of past years has been assembled in these monthly trends to affect inflationary as well as deflationary periods. The economic situation both in the United States and abroad is considered in the general make up of the trends. The manager reads the trends and the players must draw their conclusions from them and buy and sell in accordance with the interpretations they place on the trends. The tips are used to give definite hints of certain price changes of various listings, business fluctuations and business profits or earnings. They are correlated with the trends and are based on information concerning such subjects as economics, history, science and on general information.

The tips are in the form of questions and the first letter of the correct answer is the key to the tip, for example:

- Q. "What is the title of the wife of an earl?"
 A. "Countess".

70

75

If the instructions in the trends should read "metals are up" then all metals whose names begin with "C" will be in for a price advance.

In cases where the answer to a question is the name of a person, the surname and not the given name is to be used.

Some tips call for a direct answer, in which case only a single listing may be affected; this can be detected from the question and accompanying instructions.

The listings and their prices are obtained from a board whose general appearance is shown in Figs. 1, 2, 3, 4 and 5. This board is formed from a large rectangular sheet 31 whose ends and top are provided with guide slots 32 formed by the overhanging edges of the sheet 33 which is spaced from the outer surface of board 31 by narrow strips 34. A slide 35 is mounted in the guide slots and has attached to its outer surface along the lower edge a strip 36 that can be engaged by the fingers for moving the slide in the guide slots. It will be observed that the slide is provided with three spaced groups of rectangular openings 37, each group formed by three inclined lines of openings.

Attention is called at this point to the fact that the guide slot along the top of the board or the distance from the inner edge of the top spacer strip 34 and the edge 39 forming the top of the opening is much wider than the corresponding distances from the side spacer strips to edges 38. From Figs. 1, 2 and 3 it can be ascertained that the distance from the lower edge of slide 35 to the lower edge of sheet 31 is less than the distance that slide 35 projects upwardly into the upper guide slot. Since the slide does not have to move downwardly farther than the lower edge of sheet 31, it follows that the upper edge of slide 35 will always remain in the guide slot. This is important because the slide is made of cardboard or other sheet material and when it is withdrawn from the upper guide it cannot be reinserted except by pressing it down against the upper surface of sheet 31. This is due to the fact that cardboard and even metal sheets will bend and warp readily. Attention is also called to notch 43, Fig. 4 as this makes it possible to bring the lower edge of slide 35 in line with the lower edge of sheet 31 and still leave "Jan." exposed.

Referring now to Fig. 5, which represents that portion of the upper surface of sheet 31 that lies within lines 38 and 39, it will be observed that the surface is provided with three, transversely separated groups 40 of numbers. Each group comprising twelve parallel lines. The numbers are spaced equal distances vertically and are arranged in parallel and horizontal lines. At the extreme left, near the bottom, the name of the twelve months of the year are arranged in a vertical column, spaced vertically the same distances as the numbers in groups 40. January is positioned below the lowermost number in the groups. It will be observed that the numbers in the vertical column of each group, farthest to the right, are the lowest. The numbers in the next group to the left terminate one space above the lowermost number in the adjoining column to the right, and the lowest number in the column farthest to the left of each group is positioned eleven spaces higher than the corresponding number in the column farthest to the right.

In Fig. 4 slide 35 is shown superposed on the surface illustrated in Fig. 5 and elevated to such an extent that the word "December" is uncov-

ered. Openings 37 are arranged in lines inclined downwardly to the right, each hole being so positioned that a number on the chart below is visible through each hole. The surface of slide 35 is transversely ruled and has vertical lines 41 along which are printed the names of the products listed for buying and selling. The columns of listings have been designated by reference numeral 42. When the slide is in the position shown, the numbers that appear in the openings 37 are the December prices for the corresponding articles named in columns 42. Thus, under "Stock, share" the "Gas Co." stock is priced .75 while under "Produce, grains" corn is found to be quoted at .70 per bushel. If the price for any other month is desired, slide 35 is moved down until line 43 is directly over the name of the month desired, whereupon the prices for that month will appear in openings 37. It is now apparent that the prices for all of the listings can be readily obtained for any month. Attention is called to the fact that the listings are divided into six groups by the following headings: "Stocks, share"; "Live stock"; "Produce, grains"; "Business Opt.>"; "Metals, minerals" and "Monthly profit".

For convenience each player is provided with a card 44 whose front surface is shown in Fig. 7 and whose rear surface is shown in Fig. 6. On the front surface is a printed list of products, 30 identical with the list on the surface of the slide 35, except the part designated "Monthly profits". The table on the rear side of card 44 is a table used to facilitate calculations and can be used to compute the prices of blocks of stock from 1 to 5000 shares. The table is self explanatory and its manner of use is obvious.

Having described the several pieces of apparatus the manner in which the game is played will now be described.

Any number may play, but if more than four wish to play, it is advisable to play partners. In this explanation it will be assumed that there are four players and a manager and that the latter does not play but devotes his time exclusively to managing the game.

The manager assigns a safety deposit box 17 to each player and gives to each a player's card. Each player then selects \$500 worth of some commodity. The players are given no cash until the 50 settlement period at the end of the first month (the game usually starts with January) when he receives his month's salary.

The manager turns one of the knobs 23 until he brings "January Trends" into the opening 24. 55 He then proceeds to read the January trends, one by one, slowly and distinctly so that the players can grasp the meaning and the importance of each item. He then proceeds to read the tips for the benefit of the players who must apply their meanings to his own holdings.

After having read the trends and tips, the manager pauses and pays to each player his salary of \$200.00 for the month and business profits to those who own businesses.

New transactions are now made. Each player buying and selling in a manner which in his judgment, is best calculated to profit from the trends and the tips. The player's success depends on the skill with which he recognizes the 70 significance of the trends and tips and their application to their own holdings or to other products listed on the board.

After all transactions have been completed and the sales tickets filed in the proper "safety de-

posit boxes" 17 the manager moves the slide 35 so as to bring line 43 above "Feb.", whereupon the February prices of all the listed commodities, etc., appear in openings 37. The manager now 5 reads the February trends and tips, after which he pays salaries and profits. This is then followed by a new transaction period, which in turn is followed by a disclosure of March prices. This is continued from month to month until December 10 is reached, which is a "Cash in" month and for which no trends and tips are provided. Each player now turns in his holdings to the manager and receives from his payment in cash in accordance with the December prices. The player 15 having the greatest total assets wins the game, having prospered the most.

Since the players are given \$500.00 worth of listed products at the beginning of each game and are paid a salary or a business profit at the end 20 of each month, they cannot lose but are bound to prosper and end the year with, at least their December salary and/or business profit, for this reason the game has been named Prosperity.

The game is provided with a number of different trend sheets and others may be worked up from time to time and actual news items and trends arising therefrom may be employed.

In order to facilitate the drafting of claims, the board 13 will be considered as longer than it is 30 high and the designation "top" and "bottom" will be used as applied to the arrangement shown in Fig. 1.

Having described the invention what I claim as new is:

35 1. A board game apparatus, comprising in combination, a substantially rectangular card board of greater width than height, one surface of which is for the reception of printed matter, a cover board of substantially the same shape and size attached along the top and two ends to the first board, spacers between the surfaces of the two boards, positioned along the top and ends to maintain the boards in a predetermined spaced relation, the cover board having a rectangular portion removed forming a sight opening, the length of the sight opening being less than the distance between the end spacers whereby guide grooves are formed, the sight opening extending from the lower edge of the cover board to a distance less than the distance to the lower edge of the top spacer whereby an overhanging portion is provided, forming a guide groove above the sight opening, a slide of a size slightly greater than the dimensions of the sight opening, positioned with its two end edges and top side in the guide grooves, said slide being movable vertically of the board a distance slightly less than the distance from the top of the sight opening to the edge of the corresponding spacer, whereby the upper edge of the slide will at all times remain in the upper guide groove, the slide having a plurality of rows of openings extending diagonally, each row having the same number of openings of the same size, arranged in non-overlapping relation, the openings in the several rows forming vertical rows and the top opening of each lower row being on a lower level than the bottom opening in the row directly above and a finger piece on the slide to facilitate moving it.

70 2. A board game apparatus, comprising in combination, a substantially rectangular card board of greater width than height, one surface of which is for the reception of printed matter, a

cover board of substantially the same shape and size attached along the top and two ends to the first board, spacers between the surfaces of the two boards, positioned along the top and ends, to maintain the boards in a predetermined spaced relation, the cover board having a rectangular portion removed forming a sight opening, the length of the sight opening being less than the distance between the end spacers whereby guide grooves are formed, the sight opening extending from the lower edge of the cover board to a distance less than the distance to the lower edge of the top spacer whereby an overhanging portion is formed above the sight opening, a slide of a size slightly greater than the dimensions of the sight opening, positioned with its two end edges and top side in the guide grooves, said slide being movable vertically of the board a distance slightly less than the distance from the top of the sight opening to the edge of the corresponding spacer, whereby the upper edge of the slide will at all times remain in the upper guide groove, the slide having a plurality of rows of openings extending diagonally, each row having the same number of openings of the same size, arranged in a non-overlapping relation, the openings in the several rows forming vertical rows and the top opening of each lower row being on a lower level than the bottom opening in the row directly above and a finger piece on the slide to facilitate moving it.

3. A board game apparatus, comprising in combination, a substantially rectangular card board of greater width than height, one surface of which is for the reception of printed matter, a cover board of substantially the same shape and size attached along the top and two ends to the first board, spacers between the surfaces of the two boards, positioned along the top and ends, to maintain the boards in a predetermined spaced relation, the cover board having a rectangular portion removed forming a sight opening, the length of the sight opening being less than the distance between the end spacers whereby guide grooves are formed, the sight opening extending from the lower edge of the cover board to a distance less than the distance to the lower edge of the top spacer whereby an overhanging portion is formed above the sight opening, a slide of a size slightly greater than the dimensions of the sight opening, positioned with its two end edges and top side in the guide grooves, said slide being movable vertically of the board a distance slightly less than the distance from the top of the sight opening to the edge of the corresponding spacer, whereby the upper edge of the slide will in all operative positions remain in the upper guide groove, the slide having a plurality of rows of openings extending diagonally, each row having the same number of openings of the same size, arranged in non-overlapping relation, the openings in the several rows forming vertical rows and the top opening of each lower row being on a lower level than the bottom opening in the row directly above, the upper surface of the board having inclined rows of numbers, positioned and inclined so as to correspond to the openings in the slide, the board and slide having cooperating indices to facilitate positioning the slide in selected positions, and a finger piece on the slide to facilitate moving it.

HARVEY J. GRIFFITH.
